(57) **CLAIM**

The ornamental design for a desktop terminal for multimedia communication, as shown and described.

DESCRIPTION

FIG. 1 is a front and right side perspective view of the desktop terminal for multimedia communication, showing our design;

FIG. 2 is a front elevational view thereof;

FIG. 3 is a right side elevational view thereof, the left side elevational view being a mirror of the side view shown;

FIG. 4 is a rear elevational view; and,

FIG. 5 is a top plan view thereof.
